(57) **CLAIM**

(21) Appl. No.: **29/181,067**

The ornamental design for a cloth cover for a baby bottle
with elastic mouth and with see-through slot, as shown and
described.

(22) Filed: **May 6, 2003**

DESCRIPTION

(51) LOC (7) Cl. **07-01**

FIG. 1 is an isometric view of a cloth cover for a baby bottle
with elastic mouth and see-through slot showing my new
design; it being understood that the broken lines showing a
baby bottle are for illustrative purposes only and form no
part of my invention.

(52) U.S. Cl. **D24/199; D7/624.2**

FIG. 2 is a front elevational view thereof;

(58) Field of Search D24/197, 199;

FIG. 3 is a right side elevational view thereof, the left side
being identical thereto;

D7/624.2, 607, 605, 300; 215/11.1, 11.6,

FIG. 4 is a top plan view thereof;

11.3, 11.2; 248/104, 102; 200/737, 739

FIG. 5 is a bottom plan view thereof; and,

(56) **References Cited**

FIG. 6 is a rear elevational view thereof.
